UNITED STATES PATENT OFFICE.

ABRAHAM T. H. BROWER, OF CHICAGO, ILLINOIS.

PRINTING-PRESS.

1,270,779.

Specification of Letters Patent.

Patented July 2, 1918.

Original application filed November 23, 1912, Serial No. 733,165. Divided and this application filed January 22, 1917. Serial No. 143,576.

To all whom it may concern:

Be it known that I, ABRAHAM T. H. BROWER, a citizen of the United States, and a resident of Chicago, county of Cook, and 5 State of Illinois, have invented certain new and useful Improvements in Printing-Presses, of which the following is a specification.

The present application is a division of 10 an earlier application filed by me November 23, 1912, Serial No. 733,165, for improvements in printing presses, which resulted in Patent No. 1,218,049, granted March 16, 1917.

15 The invention relates to printing presses and particularly to proof presses of the bed and cylinder type. The object of the invention is to provide the cylinder with improved paper guides and grippers which 20 will clear the surface of the type and of type-high chases upon the type bed. A further object of the invention is to provide means by which the paper grippers may be released either automatically or by 25 hand as desired.

The invention consists in the features of improvement hereinafter set forth, illustrated in the preferred form in the accompanying drawings and more particularly pointed 30 out in the appended claims.

Figure 1 is an elevation of the printing press cylinder with the printing improvements applied thereto, the bed and the machine frame being shown in cross section.

35 Figs. 2 and 3 are detail sections on lines 2-2 and 3-3 respectively of Fig. 1. Fig. 4 is an end elevation of parts shown in Fig. 1. Fig. 5 is a section on the line 5-5 of Fig. 1.

The horizontal frame 10 of the press is 40 provided at intervals by transverse webs 11 and, at its upper side portions with guide rails or tracks 12 for the reciprocating bed 13. The latter is provided on its under side with longitudinal guide ribs 14 near its edges and a central longitudinal bearing rib 15, and also with transverse strengthening ribs 16. The ribs 14 and tracks 12 are preferably grooved to form race-ways for two sets of bearing balls 17 that are held 45 in proper position by spacer bars 18. The central rib 15 of the bed is arranged to engage a supporting wheel 19.

The cylinder 20 is mounted above the bed upon a shaft 21. The latter is journaled at 50 its ends in bearings carried by a pair of

brackets 22 that are bolted to and extend upwardly from the frame 10. The ends of the shaft are preferably provided with hand wheels (not shown) for rotating the cylinder. The surface of the cylinder is recessed 60 as usual, to receive the tympan and its ends are provided with bearing flanges 23 which engage the bearers 24 fixed in the usual manner to the sides of the type bed. A gear wheel 25 fixed to one end of the cylinder 65 meshes with a rack 26 fixed to one of the side edges of the bed to effect the forward and backward movements of the latter as the cylinder is rotated in opposite directions.

70 The cylinder is provided, as usual, on one side with an opening and one of the edge walls of this opening has a series of pins 28 that coöperate with a series of clamps 29 for securing one of the tympans to the cylinder. The tympan clamps are mounted upon a cross shaft or rod 30 arranged within the cylinder and journaled in the ends thereof at one end and outside of the cylinder. This shaft is provided with an arm 31 which normally engages a lug 32 to hold the tympan clamps in position. The arm 31 is formed of spring steel so that it can be shifted laterally into and out of engagement with the lug 32. The opposite 80 ends of the blankets forming the tympan pass around a pair of toothed reel rods 33 journaled within the cylinder adjacent the opposite edge of the cylinder opening. These rods are provided with square shanks 85 34 (see Fig. 5) which project beyond one end of the cylinder and are adapted to receive suitable tools for rotating the reel rods to draw the blankets tightly around the cylinder. Ratchets 35 and coöoperating 90 spring-held pawls 36 prevent the unwinding movement of the reel rods.

A series of grippers 37 for holding the leading edge of the paper against the tympan are mounted upon a rod 38 which is 100 journaled in the cylinder ends and is arranged, as shown, near the edge of the cylinder opening. A crank arm 39 on one end of the shaft 38 is connected to a hooked end of a sliding bolt 40. The latter is arranged to slide and also oscillate to a slight extent through a stud 41 fixed to the inner face of the left-hand end of the cylinder. A spring 42 coiled about this rod extends 105 between washers 43 that bear respectively 110

against the stud 41 and against a nut 44 fixed to the end of the bolt. The tension of the spring 42 is thus exerted to hold the grippers 37 against the leading edge of the tympan. The left-hand end of the gripper, shaft or rod 38 is provided with a handle 45, (see Fig. 5) by which the grippers may be oscillated and shifted to disengaged position. In the extreme disengaged position of the grippers the outer curved end of the spring bolt 40 hooks over the shaft or rod 38 so that the pivot pin between the bolt and the crank arm 39 passes beyond a dead center position. The spring 42 then acts to hold the grippers away from the tympan. The grippers are only shifted to this extreme disengaged position when it is desired to adjust the tympan. But inasmuch as the gripper spring is thus arranged to shift on opposite sides of a dead-center position it will act to yieldingly hold the grippers both in the normal position and in the extreme disengaged position.

Means is provided for shifting the grippers to a slight extent to release the leading edge of the paper and such means is so arranged that the grippers may be released either automatically or by hand. A shaft 46 extends in front of the cylinder and is journaled at its ends in the cylinder brackets 22. An eccentric cam 47 is fixed to the left-hand end of the shaft 46 and the edge of this cam engages the outer curved edge portion of the upper end of an intervening arm or trip device 48. The lower end of the arm 48 is pivotally mounted on a cross rod 49 that extends between the cylinder brackets and, on its inner edge the intervening arm or release trip is provided with an inclined cam face 50. The inclined cam portion 50 is arranged to coöperate with a roller 51 on the end of an arm 52 that is fixed to the left-hand end of the gripper shaft or rod 38. The shaft 46 is provided at its extreme left-hand end outside of the bracket 22, with a handle 53 (see Fig. 1) and at the opposite side of the machine (see Fig. 4) it is provided with a handle 54 having an enlarged notched hub 54'. A dog 55 pivoted on the right-hand end of the rod 49 is pressed toward the notched hub by a spring 56 which extends between the dog and a lug 57 on the face of the right-hand bracket 22. The movement of the eccentric cam 47 and intervening arm 48 is limited in one direction by the engagement of the curved inwardly projecting end of the handle 53 with the edge of the adjacent bracket 22. In the opposite direction the movement of these parts is limited by the engagement of a toe piece 58 (see Fig. 5) on the pivot end of the intervening arm or releasing trip 48 and with a projecting lug 59 on the inner face of the left-hand bracket 22.

With the low part of the eccentric cam

47 in engagement with the intervening arm or release trip 48 the roller 51 on the crank arm 52 will clear the inclined cam face 50 so that the grippers will not be automatically released. But in the initial position of the cylinder the shaft 46 can be rotated on either side of the machine by means of either of the handles 52 or 53 to thereby force the upper end of the arm 48 against the roller 51 so that the gripper shaft 38 is rocked against the tension of the spring 42 to release the grippers. The paper may be then placed in position on the cylinder with its front edge against the guides provided therefor and then, by releasing the eccentric cam 47, the spring 42 will shift the grippers to engage the paper.

If desired, the eccentric cam 47 can be held in shifted position by means of the dog 55 on the right-hand side of the machine so that the grippers will be automatically released at the end of the forward movement of the cylinder and will be automatically returned to position to grip the paper after the cylinder is moved forward to disengage the roller 51 from the inclined cam face 50 of the intervening arm or trip device 48. The hub 54' with which the dog 55 coöperates is provided with a series of notches so that the dog serves to hold the cam and trip arm in any one of a number of positions. In the position shown the grippers must be released by hand. In the positions corresponding to the other notches, the grippers are automatically released and restored at different points. The ends of the dog and the notches of the hub 54' are provided with oppositely inclined faces so that the shaft 46 and cam 47 can be readily turned or adjusted as desired by means of the handles 53 and 54.

The front guides for the leading edge of the paper comprise a series of U-shaped fingers 60 which are mounted upon a rod 61 and extend around the edge of the cylinder opening. This rod is journaled in the ends of the cylinder and at its left-hand end has an arm 62 fixed thereto. A cushion spring 63 extends between the end of this arm and the end of an arm 64 which is loosely mounted upon the rod 61, the arrangement being such that the arm 64 is pressed by the spring 63 against the cylinder wall. This spring serves to yieldingly hold the front guide fingers in operative position. Preferably, as shown, the front guide fingers 60 are provided at points in line with the surface of the tympan with shoulders 65 to aid in accurately positioning the paper on the cylinder.

The outer face of the cylinder adjacent the edge of the cylinder opening is cut away so that the grippers lie within the periphery of the cylinder and bearing flanges 37 and will therefore clear the sur-

face of the type and chase upon the bed 13. Means are provided for shifting the front paper guides 60 so that they will also clear all portions of the type surface. For this purpose the guide rod or shaft 61 is provided on its left-hand end with an arm 66 (see Fig. 5) having a roller 67 on its end. As the cylinder is rotated and as the guide fingers approach the type surface, the roller 10 67 engages a fixed curved cam ledge 68 which is secured to the inner face of the left-hand bracket 22 by studs 69 (see Figs. 1 and 5). The greater portion of the cam ledge or track 68, as shown in Fig. 5, is 15 concentric with the axis of the cylinder and it is provided with inturned cam portions at its ends which engage and shift the roller 67 outwardly and permit its return movement to normal position as the cylinder is 20 rotated in opposite directions. The engagement of the roller 67 with the cam ledge 68 thus shifts the shaft 61 against the tension of the spring 63 and automatically withdraws the front guide fingers 60 into the 25 cylinder and holds them withdrawn so as to clear the type and all portions of any type-high chase on the bed during both the forward and backward movements of the bed and cylinder. A sleeve 70 fits over the rock 30 shaft 46 and interlocks with the part 71 on the right-hand cylinder bracket 22 so that it is held against movement. The shaft 46, however, is free to rock within this sleeve. A series of brackets or collars 72 are fixed 35 to the sleeve 70 and a series of sheet guiding bands 73 are provided with doubled offset portions 74 which are riveted together and the outer looped ends of which encircle the rod 49.

40 In operation, the paper sheet is placed on the cylinder with its leading edge engaging the guide fingers 60 and the shoulders 65 thereof so that these will be clamped by the grippers 37. If necessary, the grippers 45 are shifted by means of the cam 47 on the shaft 46 and the intermediate trip arm 48, as described before the edge of the paper is engaged with the guide fingers. As above noted, the intermediate trip arm 48 may be 50 held in such position by the cam 47, that in the normal position of the cylinder the grippers will be held released but will engage the forward edge of the paper as soon as the initial movement of the cylinder disengages 55 the roller 51 from the inclined cam face 50. The cylinder is then rotated to shift the bed and carry the paper on the cylinder into engagement with the type on the bed. At the 60 end of a single revolution of the cylinder in forward direction, the grippers 30 are released either by hand or automatically and the paper is removed from the cylinder. The latter is then rotated in the opposite direction to initial position. During the 65 forward and backward movements of the

cylinder and bed, the roller 67 on the arm 68 shifts the guide fingers 60 into a position within the cylinder so that they will not contact with the type or with the type-high chase. 70

It is obvious that changes may be made in the details set forth without departure from the essentials of the invention as defined by the claims. 75

I claim as my invention: 75

1. In a printing press, the combination with a frame, type bed, cylinder and cylinder supporting brackets, of paper grippers carried by said cylinder, a releasing trip for said grippers and a transverse, manually operable rock shaft journaled in said cylinder brackets for actuating and adjusting said releasing trip, said rock shaft having operating handles at opposite sides of the press. 80

2. In a printing press, the combination with the frame, cylinder and reciprocating type bed, of a series of front paper guides mounted on said cylinder and normally spring-held in projected position, a fixed cam on the frame and a part on said cylinder co-operating with said cam to shift said guides inwardly and to hold the same in such position to thereby clear the type and type chase on said type bed as the cylinder 90 is rotated. 95

3. In a printing press, the combination with the frame, cylinder and reciprocating type bed, of a rock shaft within said cylinder, a series of front paper guides carried by said shaft, a spring for holding said shaft and guides in normal position, an arm on one end of said rock shaft, and a fixed track on the frame concentric with the axis of said cylinder and having cam-shaped ends, said cam track being adapted to co-operate with said arm for shifting said guides inwardly, holding the same in such position as said cylinder is rotated in opposite directions. 105

4. In a printing press, the combination with the frame, cylinder and reciprocating type bed, of a pair of spring-held rock shafts mounted within said cylinder, grippers and front paper guides fixed respectively to said rock shafts, the portion of the tympan surface engaged by said grippers being cut away so that the latter in normal position, are arranged within the cylindrical portion of the tympan surface, means for tripping said gripper rock shaft, an arm on said front guide rock shaft, and a cam on the frame co-operating with said arm to shift said front guides inwardly and hold the same in such position to thereby clear the type and type chase as the cylinder is rotated in opposite directions, substantially as described. 115 120 125

5. In a printing press, the combination with the frame, cylinder and reciprocating 130

type bed, of a pair of spring-held rock shafts mounted within said cylinder, grippers and front paper guide fingers fixed respectively to said rock shafts, said guide fingers having shoulders in line with the tympan surface of said cylinder for engaging the front edge of the paper, a releasing trip for said gripper rock shaft, means for operating said trip, and a cam on the frame 5 controlling said guide finger rock shaft, substantially as described.

6. In a printing press, the combination with the frame, cylinder and reciprocating type bed, of front paper guides and grippers mounted on said cylinder, a releasing trip for said grippers, and means for operating said trip by hand and for adjusting the same to operative position to automatically shift said grippers.

20 7. In a printing press, the combination with the frame, cylinder and reciprocating

type bed, of a spring-held rock shaft on said cylinder, a series of paper grippers on said shaft, an arm on said rock shaft, a releasing trip on the frame co-operating with said arm, 25 a cam for shifting said trip into and out of operative position, and a locking dog for releasably securing said cam and trip in operative position.

8. In a printing press, the combination with the frame, cylinder and reciprocating type bed, of a rock shaft in said cylinder, a series of paper grippers carried by said rock shaft, an arm on said rock shaft, and a spring actuated bolt in said cylinder having 30 a U-shaped hooked end connected to said arm and arranged to hold said grippers either in operative or in inoperative position, said U-shaped end, in one such position, being arranged to hook over said shaft.

ABRAHAM T. H. BROWER.
